UNITED STATES PATENT OFFICE.

FREDERICK RAPP, OF CHICAGO, ILLINOIS.

DESIGN FOR A WATCH-CASE.

SPECIFICATION forming part of Design No. 16,885, dated August 31, 1886.

Application filed June 21, 1886. Serial No. 205,891. Term of patent 7 years.

To all whom it may concern:

Be it known that I, FREDERICK RAPP, a citizen of the United States, residing at Chicago, in the county of Cook and State of Illinois, have invented a certain new and original Design for Watch-Cases, which is fully set forth in the following specification, reference being had to the accompanying drawings, forming a part hereof, and in which--

10. Figure 1 is a side view of my newly designed watch-case, showing the same closed, and Fig. 2 shows the same view with the cover of the case open.

Fig. 1 shows a watch case in the form of a bird, the lid or cover of the face being represented by a circle, over which the plumage extends beyond the circle and without interruption, as if no line of separation were there, the side of the body being quite flat, as clearly 20 shown, while in Fig. 2 the face of the watch is shown open, and the stem is expanded at its

outer end so as to form a perch, upon which the feet of the bird rest.

The leading feature of my design consists of a flat watch case in the form of a bird, executed 25 as shown.

What I claim is--

1. The design for a watch-case herein described and shown, the same being fashioned in the form of a bird, having flat sides, upon 30 which the plumage is illustrated.

2. The design for a watch-case herein described and shown, the same being fashioned in the form of a bird, having flat sides, and represented as upon a perch formed of the expanded end of the stem, and showing plumage upon the sides. 35

FREDERICK RAPP.
